UNITED STATES PATENT OFFICE.

JAMES S. LANG, OF WATERTOWN, MASSACHUSETTS.

SHOCK ABSORBER.

Application filed January 8, 1921. Serial No. 435,936.

To all whom it may concern:

Be it known that I, JAMES S. LANG, of Watertown, in the county of Middlesex and State of Massachusetts, a citizen of the United States, have invented a new and useful Improvement in Shock Absorbers, of which the following is a full, clear, and exact description, reference being had to the accompanying drawings, forming a part of this specification, in explaining its nature.

The present invention relates to a shock absorber especially designed to be used in connection with automobiles or other vehicles and constitutes essentially an improvement in the type of shock absorber shown and described in Letters Patent of the United States No. 1,269,289, granted me June 11, 1918, and also my Letters Patent of the United States No. 1,379,191, of May 24, 1921.

The object of my invention is to increase the efficiency and make more perfect the type of shock absorber described in my patents before mentioned.

The improved shock absorber constituting my invention can best be seen and understood by reference to the drawings, in which—

Figure 1 shows the device in front elevation.

Fig. 2 is a side elevation.

Fig. 3 is an elevation on line 3—3 of Fig. 4.

Fig. 4 is a vertical section of the device.

Fig. 4^a is a vertical section of the device in slightly modified form and to which special reference will later be made.

Fig. 5 is a vertical section of the device showing the engaging position of the operating parts.

Fig. 6 is a cross section of the device.

Figs. 7 and 8 are plans showing certain details of construction.

1 is the friction blade preferably made in two sections 2 and 2' and provided with an attachable end 3. The blade section 2' is preferably tapered, its thickness generally increasing in the direction of its attachable end.

Engaging the blade sections 2 and 2' are friction shoes 4, 5 and 6.

7 is the carrier or casing for the shoes provided with an attachable end 8.

The shoes are nested together to be movable in a restricted endwise direction on

and relatively to the carrier and likewise have a permitted movement of translation relatively to the friction blades, substantially as described in my said Patent No. 1,379,191. During their endwise movement the shoes run on rollers 9 interposed between the shoe 6 and the back of the carrier, and a spring 10 located within the back of the carrier acts normally to throw the shoes in the direction of the attachable end of the blade sections and into what will later be referred to as their engaging position relatively to the blade sections.

The general structure and arrangement of the blade sections, shoes and carrier and their mode of operation are substantially as shown and described in my said Patent No. 1,379,191 excepting the manner in which pressure is applied for constricting the unit comprising the blade sections and shoes and to which changed manner of applying pressure reference will now be made.

Secured to spaced bosses 11 on opposite sides of the carrier 7 and located beyond the forward end or open face of the carrier is a keeper 12 preferably in the nature of a rectangular plate secured to the carrier by bolts 13 which are threaded and fit into the bosses 11.

Arranged within the keeper is a bow spring 15 of considerable tension and preferably made up of a number of leaves. The spring is so arranged that its outturned or central body portion projects in the direction of the shoe 4 with the opposite ends of the spring engaging the inner face of the keeper. The spring is preferably shaped to present a central portion substantially equal in width to the width of the keeper and thence narrowing to the ends of the spring. These ends at the points of their engagement with the inner face of the keeper lie loosely within a raised rib or flange 16 with which the under side of the keeper is provided and which acts to hold the spring against endwise and lateral displacement, permitting, however, of the extension thereof when the spring is flattened in the direction of the under side of the keeper.

Co-ordinating with the inner face of the spring and movable with it is a member 17 which forms a bearing for a roller 18 interposed between the bearing 17 and a bearing 19 on the outer side of the shoe 4. The

2
member or bearing 17 may be supported in any suitable manner. As shown, the member is secured to a crossbar 20 journaled to turn in ears 21 downturned from the inner side of the keeper at one end thereof.

5 The bearings 17 and 19 are provided, respectively, with surfaces 22, 23, on which the roller runs as the shoes are moved relatively to the carrier. During such movement the roller is held against lateral displacement by spaced flanges 24 on the bearing 17, while its travel in reverse directions is limited and defined by spaced flanges 25 on the bearing 19, the respective sets of flanges 24, 25 forming a socket within which the roller is contained.

10 The surfaces 22, 23 on which the roller runs are so relatively disposed that, at the bottom end of the socket within which the roller 18 is contained, the distance separating the surfaces substantially equals the diameter of the roller, assuming the spring 15 to be under little or no compression, but from this end of the socket the surfaces 15 gradually converge to the opposite end of the socket. Consequently as the shoes are movable upon the carrier the roller will be actuated to exert through the bearing 17 a gradually increasing or a gradually diminishing 20 pressure upon the spring 15. Pressure thus exerted tends to flatten the spring in the direction of the keeper with the resulting effect that the tension of the spring will exert pressure upon opposite sides of the unit comprising the blade sections and shoes tending to 25 constrict the same and thereby increase the friction bearing of the shoes against the blade sections. Such pressure of the spring is exerted back through the roller 18 against the shoe 4 and also through the carrier 7 and rollers 9 against the shoe 6.

30 The operation is as follows:—

35 It will first be assumed that the attachable ends of the blade sections are secured to the spring supporting the vehicle or to the body of the vehicle directly by any suitable fastening (not shown) and that the attachable end of the carrier is attached either to that portion of the spring secured to the axle or to the axle itself by any suitable fastening (not shown). It will also be assumed that the blade sections are occupying a relationship 40 partially drawn out from the nest of friction shoes and that the spring 10 has tended to throw the blade sections in the direction of their attachable end and in consequence the roller 18 has been moved to a position between the surfaces 22 and 23 where it will tend to flatten the spring 15 and pressure be 45 thereby applied to the friction shoes for pressing them against the blade sections as above outlined. This, in other words, is the normal position of the operating parts.

50 Assuming, now, that the operation of the vehicle has tended to compress the vehicle

55 spring. Thereupon the blade sections will move downwardly through the nest of friction shoes. As this action continues the friction grip of the shoes upon the blade sections will gradually tend, owing to the increasing thickness of the section 2', to overcome the tension of the spring 10. That is, the blade sections will finally move downwardly to a point where they will carry the shoes with them and thereupon move the 60 shoes to the limit of their downward end-wise movement limited by the carrier as aforesaid. During such movement of the shoes the spring 10 will be compressed and the roller 18 moved into a position where it will no longer tend to compress the spring 15, accordingly releasing the pressure against the friction shoes. Thereupon the 65 progress of the blade sections through the shoes will continue substantially unimpeded until the vehicle spring has reached a point of full compression and with the resulting tendency for the vehicle spring to rebound with the usual backlash. At the instant this occurs the blade sections will be suddenly drawn upward and the spring 10 will return the shoes to their initial engaging position when pressure will be applied to the shoes by the return of the roller 18 to a position where it will tend to flatten the 70 spring 15 with the resulting action above explained. Pressure thus applied to the shoes will tend to govern the backlash of the vehicle spring and prevent a too disruptive action. As the retraction of the 75 vehicle spring continues the blade sections will continue to be drawn out of the nest of shoes, the pressure of the shoes against the blade sections becoming gradually less and less as the section 2' decreases in thickness 80 until the vehicle spring resumes its normal position when the action is repeated as the vehicle spring is again compressed.

85 Instead of the roller 18 operating between surfaces 22, 23 for flattening the spring 15 as above explained, there may be employed an elliptical roller 18' as shown in Fig. 4^a operating between bearings 22', 23', the elliptical roller 18' being substantially the same type of roller as that shown and described in my said patent and functioning substantially as described in said patent.

90 I also prefer that the rollers 9 interposed between the shoe 6 and the back of the carrier should be elliptical rollers as described in said patent for assisting in flattening the spring 15 during the operation of the device, for it will be apparent that by employing such type of roller the carrier will be displaced laterally during the operation of the device and by such displacement tend either to flatten the spring 15 or enable it to relax 95 dependent upon the direction of movement of the shoe 6 which initially operates to actuate the rollers.

Apart from the function imparted to the rollers as above described it will also be observed that the rollers act as friction-eliminating members or elements upon which 5 the shoes may ride, thereby improving the device in point of facility of operation and eliminating wear.

It is apparent that the degree of pressure imparted to the friction shoes for pressing 10 them against the blade sections will depend upon the position of the keeper. I have accordingly provided means whereby the keeper may be adjustable in order that the variation in pressure may be obtained. 15 Such adjustment is effected simply by turning the bolts 13 by which the keeper is secured to the carrier, in or out with relation to the carrier, the adjustment of the bolts, in other words, giving adjusted position to 20 the keeper. After the adjustment of the bolts and keeper has been obtained the heads 26 of the bolts will slip into sockets 27 with which the outer face of the keeper is provided, the tension of the spring 15 25 against the keeper acting to press the keeper against the heads of the bolts and thereby maintain the bolts within the sockets when the keeper will act as a lock to prevent accidental turning of the bolts.

Having thus fully described my invention, I claim and desire to secure by Letters Patent of the United States:—

In a shock absorber, the combination comprising a friction blade, a friction shoe arranged to engage said blade, a carrier for the shoe with relation to which the shoe is retained to have a limited endwise movement, a keeper fixed to the carrier and occupying a position spaced from the outer side of said shoe, a tension member interposed 35 between said keeper and said shoe adapted when actuated to exert pressure for pressing said shoe against said blade, a bearing movable with said tension member, means for pivotally supporting said bearing, a bearing 40 on said shoe, and a member interposed between said bearings, said bearings and interposed member presenting surfaces co-operating with one another whereby said interposed member may have a determinate rolling contact with said bearings during the endwise movement of said shoe relatively to the carrier and simultaneously with such rolling contact said bearings be displaced laterally in relation to one another for actuating said tension member to exert pressure as aforesaid. 45 50 55

JAMES S. LANG.
